UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL-STOVE.

1,369,029.

Specification of Letters Patent. Patented Feb. 22, 1921.

Application filed July 10, 1919. Serial No. 309,879.

To all whom it may concern:

Be it known that I, RUDOLPH HOFFMAN, a citizen of the United States, residing at Kankakee, in the county of Kankakee and 5 State of Illinois, have invented certain new and useful Improvements in Oil-Stoves, of which the following is a specification.

The invention relates to oil stoves and more particularly to improved means for 10 mounting the oil reservoir thereof, the aim being to mount the reservoir in such a manner that it will be securely held in place and at the same time may be quickly and easily removed for filling or other purpose.

15 In the accompanying drawings, wherein I have illustrated a preferred embodiment of the invention, Figures 1, 2 and 3 are fragmentary top, side and end views, respectively, of a stove having a reservoir mounted 20 thereon in accordance with my invention. Fig. 4 is a fragmentary side elevation showing the parts swung into position to permit of the removal of the reservoir. Fig. 5 is a fragmentary vertical section taken on line 25 5—5 of Fig. 3. Fig. 6 is a horizontal section taken on line 6—6 of Fig. 5. Fig. 7 is an enlarged fragmentary sectional view taken in the plane of lines 7—7 of Fig. 6. Fig. 8 is an end view of the stove top showing 30 a detail of construction.

In the drawings 1 indicates a stove frame having a top 2. 3 is a reservoir in the form of a glass bottle, and 4 is an oil well with which the reservoir normally communicates 35 and from which leads an oil feed pipe 5. The reservoir is detachably secured to a pivoted frame 6, and an extension top 7 is mounted so as to swing into position to permit of the easy removal of the reservoir from 40 said frame when the latter is swung with the reservoir into the position shown in dotted lines in Fig. 4.

To support the reservoir 3, the oil well 4, and associated parts upon the stove, I provide at one end a bracket which may be formed by a pair of side plates 8 spaced apart and connected by a top plate 9 (Fig. 5). Said top plate has an aperture 10 therein opening into the well 4 which is suitably 50 secured upon the under side of the top plate. The reservoir 3 on its under side and centrally thereof has an outlet nozzle or neck 11 which is arranged to discharge into the well 4 when the reservoir is in its normal or 55 operative position. In this position of the

reservoir a valve member 12 in the neck 11 is held in its open position against the action of a spring 13 by a stem 14 engaging with the bottom of the well 4 (Fig. 7). Said spring bears between a cage 15 entered within the neck and having a portion fixed to the outer periphery thereof, and a seat for the valve member 12 is formed by a shallow cup or plate 16 rigid with the cage 15 and having an opening 17 therein through which the 60 valve stem depends. It will be seen that when the reservoir is supported in its normal position, the oil will flow into the well 4, to a height determined by the pressure of the atmosphere upon the surface of the oil in 65 the well. From the well the oil is conducted to the stove burners (not shown) by means of the feed pipe 5.

The frame 6, to which the reservoir is detachably secured, is in the form of a flat 75 plate having downturned flanges 18 at each side edge. Said flanges are pivoted at 18^a to the outer ends of a pair of links 19 the inner ends of which are slidably connected to the bracket plates 8 as by means of a 80 cross pin 20 (Fig. 6) operating in slots 21 in said plates. When in normal position, the frame is arranged to rest upon the top plate 9 of the bracket with the side flanges 18 depending along the side plates 8 (Fig. 85 3 and dotted lines Fig. 6). For receiving the neck of the reservoir, the frame has a central rearwardly opening slot 22 (Fig. 6) of a width less than the diameter of the plate 16 which is rigid with the reservoir. The 90 parts are so proportioned that when the neck of the reservoir is entered in the slot 22 with the plate 16 beneath the top plate of the frame 6, the reservoir is held in position thereon. When it is desired to remove the 95 reservoir for any purpose, as for replenishing the supply of oil, it is only necessary to swing the frame upwardly and outwardly into substantially inverted position (dotted lines Fig. 4) whereupon the reservoir may 100 be readily removed by withdrawing its neck from the slot.

Normally, the extension top is arranged to prevent the upward swinging movement of the reservoir, and to permit of such movement and hence the free removal of the reservoir, the extension top 7 is swingably mounted as for example upon the reservoir supporting bracket; and in order that the 105 flow of oil from the reservoir into the oil 110

well 4 shall be promptly cut off by the valve member 12, in the removing operation, said top 7 is preferably so connected with the frame that when the top is swung into operative position as a necessary preliminary to the removal of the reservoir the latter will be raised a sufficient distance to lift the valve stem 12 from off the bottom of the well 4. To this end the extension top 7 is mounted upon a pair of bent arms 23 which are pivoted at 24 to the side plates 8 of the supporting bracket with washers 24^a therebetween. Said arms are in turn pivotally connected by links 25 to the links 19 slidably connected to the bracket. The links 25 are provided with stop lugs 25^a (Fig. 6) on their rear side edges adapted to limit the swinging movement thereof relative to the arms 23 in one direction.

The parts are so arranged that as the extension top is swung downwardly from the position shown in Fig. 2 to that shown in Fig. 4, the links 19 and thereby the frame 6 are first swung upwardly and then moved forwardly until stopped by the pin 20 engaging with the forward ends of the slots 21. The frame 6 and reservoir 3 may then be swung forwardly and downwardly into inverted position. To limit such swinging movement of the frame, I provide at each side edge thereof at its forward end a pair of stop lugs 26 formed by bending the forward edge of the top plate of the frame, slightly widened at this point, upon itself as shown at 27 (Figs. 5 and 6). These lugs, as the frame is swung downwardly, engage with the lower edges of the links 19, (as shown in dotted lines Fig. 4) and thus limit such swinging movement of the frame, the arrangement preferably being such that the reservoir may finally rest upon the inner end of the extension top 7 as shown in Fig. 4. From such position, it will be apparent, the reservoir is free to be withdrawn from the frame as above set forth.

To replace the reservoir in position upon the stove, it will of course be understood that the reverse operation to that just described takes place, the reservoir being first slid into position with reference to its frame which is then swung into position between the links 19. Thereupon by swinging the extension top 7 upwardly into its horizontal position the frame and reservoir are lowered into their normal position. For holding the extension top in this position, it may be provided with a pair of latch members 7^a adapted to operatively engage with the stove top (Fig. 5); and for preventing the reservoir from swinging out of its proper or normal position, a stop member 28 is provided projecting forwardly from the stove frame, being herein made integral with the top plate 9 of the supporting bracket. The latch members may be rigidly

secured to the inner sides of the side flanges of the extension top and engage in slots 7^b in the end flange of the stove top 2 (Fig. 8). The extension top while fixed with reference to the arms 23, is adapted to spring sufficiently to permit the insertion and removal of each of the latch members relative to its slot.

It will be seen that I have provided means of a practical character for mounting the oil reservoir of an oil stove. The operation of removing the reservoir is very simple and yet is normally firmly and safely held in position, being free from danger of removal by small children.

While I have herein illustrated and described the invention with considerable particularity it is to be understood that in the interpretation of the annexed claims they are not to be limited except as may be necessitated by the state of prior art.

I claim as my invention:

1. In combination with a stove frame, a supporting bracket at one end of said frame including a pair of side members and a top member, an oil well secured on the under side of said top member, said top member having an aperture therein, a pair of links slidably and pivotally connected at their rear ends with said side members of the bracket, a member pivoted at its forward end between said links, an oil reservoir having a sliding connection with said member so as to be detachable therefrom when the member is swung in a direction away from the stove frame, said reservoir having an outlet normally discharging into said oil well, a valve in said outlet adapted to close the same when the reservoir is raised, and a swingably mounted top for said reservoir operatively connected with said links whereby when the top is swung forwardly and downwardly the links together with the reservoir are moved forwardly and upwardly.

2. In combination with a stove frame, a supporting bracket at one end of said frame including a top member, an oil well secured on the under side of said top member, said top member having an aperture therein opening into said well, a frame pivotally connected at its outer end with said bracket and including a portion overlying said top member of the bracket and having a rearwardly opening slot, and an oil reservoir having on its underside a discharge nozzle capable of entering said slot and provided with a plate on its lower end of greater diameter than the width of said slot whereby to hold the reservoir in position on the pivoted frame and to permit the withdrawal of the reservoir when the frame thereon is swung away from the stove frame, said reservoir nozzle being arranged to normally discharge into said well.

3. In combination with a stove frame, a supporting bracket at one end of said frame, an oil well carried by said bracket, an oil reservoir having an outlet arranged to normally discharge into said well, a supporting member carrying said reservoir and swingable into position away from the stove frame to permit the detachment of the reservoir, a top for the reservoir normally preventing such swinging movement of the frame and adapted to swing forwardly and downwardly, said top being operatively connected with said frame whereby in its swinging movement the frame is moved forwardly and upwardly, and means for limiting the swinging movement of the frame.

4. In combination with a stove frame, a supporting bracket, a member pivoted at its rear end and terminating adjacent said stove frame, said member including a plate having a rearwardly opening slot, a reservoir adapted to slidably engage in said slot and adapted to be removed from the member when the latter is swung in a direction away from the stove frame, and means for limiting the extent of swinging movement of said pivoted frame.

5. An oil stove having, in combination, an oil reservoir, a top for said reservoir, a pivoted frame carrying said reservoir and adapted to permit of its detachment when swung substantially into inverted position, said top being adapted to normally prevent such swinging movement of the frame and reservoir but being swingable into position to permit it.

6. An oil stove having, in combination, an oil reservoir having a discharge outlet, a pivoted frame having an apertured plate to which the reservoir is detachably secured

and adapted to permit the withdrawal of the reservoir when swung substantially into inverted position, an oil well into which said reservoir normally discharges, and a valve acting to close said outlet when the reservoir is raised in the operation of inverting said frame.

7. An oil stove having, in combination, an oil reservoir having a discharge outlet, a slidably supported pivoted frame to which the reservoir is detachably secured and adapted to permit the withdrawal of the reservoir when swung substantially into inverted position, an oil well into which said reservoir normally discharges, a top for said reservoir swingable into position to permit the swinging of the frame into inverted position, said top being operatively connected with said frame whereby in the initial swinging movement thereof the frame is raised and moved outwardly on its support, and a valve acting to close said reservoir outlet as the reservoir is raised.

8. In an oil stove having a frame, an oil reservoir, means for supporting the reservoir upon the frame including a bracket having a top portion with an opening therein and a member movably mounted on said bracket and normally retaining said reservoir in position, said reservoir having an outlet adapted to normally discharge into said well, and a top for said reservoir normally preventing the removal thereof but swingable into position to permit the release of the reservoir by the operation of said movable member.

In testimony whereof I have hereunto set my hand.

RUDOLPH HOFFMAN.
